UNITED STATES PATENT OFFICE.

HENRY WILSON, OF TARR FARM, PENNSYLVANIA.

IMPROVEMENT IN PIPE-WRENCHES.

Specification forming part of Letters Patent No. 118,997, dated September 12, 1871.

To all whom it may concern:

Be it known that I, HENRY WILSON, of Tarr Farm, in the county of Venango and State of Pennsylvania, have invented a new and Improved Pipe-Wrench; and I do hereby declare that the following is a full, clear, and exact description thereof, which will enable others skilled in the art to make and use the same, reference being had to the accompanying drawing forming a part of this specification, in which—

Figure 1 represents a side view of my improved pipe-wrench. Fig. 2 is an edge view of the same.

Similar letters of reference indicate corresponding parts.

This invention relates to a new pipe-wrench, in which the movable jaw is pivoted to the shank of the lower jaw and by a projecting pin connected with slotted arms of the pivoted handle, whereby considerable leverage is gained and the power of gripe consequently increased.

A in the drawing represents the lower jaw of the pipe-wrench rigidly affixed to a handle, B.

C is the other handle of the wrench, pivoted at *a* to the handle B, and forked at its upper end, as shown. D is the movable jaw, pivoted at *b* to the upper part of the handle B. *c* is a pin projecting from the sides of the jaw D through slots *d* in the forked upper part of the handle C. Whenever the lower end of the handle B is carried toward the handle its forked upper end will swing the jaw with great power toward the jaw A for holding a pipe or other thing.

Having thus described my invention, what I claim as new, and desire to secure by Letters Patent, is—

The combination of the jaw A and handle B with the forked and slotted handle C, pin *c*, and jaw D, all arranged substantially as herein shown and described.

HENRY WILSON.
